J. DE W. SMITH
ROTARY ONE-PERSON SEESAW

Des. 159,451

Filed May 25, 1949

James De Walt Smith

UNITED STATES PATENT OFFICE

159,451

ROTARY ONE-PERSON SEESAW

James De Walt Smith, Towanda, Pa.

Application May 25, 1949, Serial No. 2,882

Term of patent 14 years

(Cl. D34—15)

To all whom it may concern:

Be it known that I, James De Walt Smith, a citizen of the United States, residing at Towanda, in the county of Bradford and State of Pennsylvania, have invented a new, original, and ornamental Design for a Rotary One-Person Seesaw, of which the following is a specification, reference being had to the accompanying drawing, forming part thereof.

In the drawing Fig. 1 is a perspective view of a rotary one-person seesaw, showing my new design.

Fig. 2 is a plan view, and

Fig. 3 is a view in front elevation.

I claim:

The ornamental design for a rotary one-person seesaw, as shown.

JAMES DE WALT SMITH.
